UNITED STATES PATENT OFFICE.

HARDY H. HAIR, OF NEWPORT BEACH, AND CHASE E. SUTTON, OF LOS ANGELES, CALIFORNIA.

DEVICE FOR TAKING CORE SAMPLES IN ROTARY DRILLING.

Application filed April 11, 1923. Serial No. 631,287.

To all whom it may concern:

Be it known that we, HARDY H. HAIR and CHASE E. SUTTON, citizens of the United States, residing in Newport Beach, county 5 of Orange, State of California, and Los Angeles, county of Los Angeles, State of California, respectively, have invented new and useful Improvements in Devices for Taking Core Samples in Rotary Drilling, 10 of which the following is a specification.

This invention relates to improvements in means for taking samples of the formation being drilled through in sinking wells, such as oil, or water wells, or other bore 15 holes; and relates, in its more specific aspect more particularly to the taking of samples or cores, as they are usually termed, in rotary drilling operations. And the improvements of the present invention also 20 relate more particularly to that general type of core taking apparatus that is described in the application for U. S. Letters Patent on device for taking core samples in rotary drilling, by Hardy H. Hair, February 27th, 25 1922, Serial No. 539,392. The present invention has to do with several matters of improvement in such apparatus, to facilitate the taking of the cores, to facilitate their removal from the core barrel, to facilitate 30 the mounting and removal of the core barrel on the drilling bit, and various other things that will be well understood from the following detailed specification. All of the objects and corresponding features of 35 accomplishment of the invention will be best understood from an understanding of a specific and preferred form of device illustrative of the invention; and accordingly I proceed to a detailed description of such a 40 device, reference for that purpose being had to the accompanying drawings in which—

Fig. 1 is a vertical longitudinal section showing our improved core taking apparatus mounted in a typical form of rotary drilling bit;

Fig. 2 is a cross section on line 2—2 of Fig. 1;

Fig. 3 is a cross section on line 3—3 of Fig. 1;

Fig. 4 is an enlarged cross section on line 4—4 of Fig. 1; and

Fig. 5 is an enlarged longitudinal section showing a slight modification of structure of the upper end of the core barrel.

In the drawings we show at 10 the body

or mandrel of a drilling bit of the disk cutter type, this mandrel carrying two disk cutters 11 whose operation is well understood in the art. We mount a core barrel 12 in a central vertical position in mandrel 10, the core barrel preferably, in the form here illustrated, extending in one piece from a point near the cutters 11 upward to a point above the mandrel. Thus, the major part of the core barrel, designated by the 60 numeral 13 in the drawings, may preferably be formed of a piece of heavy walled pipe, such as extra or double extra heavy hydraulic pipe. Its lower end carries a cutter shoe 14, the details of which will be explained; and at its upper end it has a core barrel extension 15 whose details will be explained. This extension may be of any suitable length, depending upon the length of core sample it is desired to take; and, as 65 will be noted from the drawings, the upper end of barrel 13 and the extension 15 project upwardly into the hollow interior of the drill pipe or stem 16 whose lower end connects with mandrel 10 through the taper 70 pin-and-socket joint 17.

Shoe 14 is mounted on the lower end of a barrel section 13 by means of a threaded and shouldered joint as illustrated at 18. This thread may either be straight or 75 tapered and it is preferably designed to give the shoe a joint of maximum strength with the barrel, and the threads furthermore may be fitted tightly enough that they will not be likely to unscrew if the bit is rotated 80 reversely to its normal direction of rotation. The normal direction of rotation is right-handed; and the thread at 18 is also right handed so that there is normally a 85 tendency to tighten it. This joint 18 is placed high enough so that when it is removed a clear open space is left adjacent nuts 11^a of disks 11. This facilitates 90 removal of the disks for sharpening without the necessity of removing the whole core barrel. The opening 14^a through shoe 14 is smaller than the opening through barrel 13; and I prefer to make this opening 14^a taper toward its lower end, so that the opening 95 at the extreme lower end of the shoe is substantially smaller than the opening in the barrel. At its lower edge shoe 14 has formation cutting teeth 14^b that will cut into the formation and separate a core that will rise in the barrel as the bit and the core bar- 100

110

rel move downwardly. We make the shoe opening smaller than the barrel opening so that the core cut by the shoe will not have a tendency, or at least any great tendency, to bind and stick in the barrel. And for this same purpose we make the interior diameter of barrel extension 15 preferably somewhat larger than that of barrel section 13 (see the increase in diameter at the point marked 20 in Fig. 1).

For the purpose of easily removing a core from the lower part of the barrel, or shoe, the shoe may be split longitudinally as at 14^a. The upper ends of the halves are held together by joint 18; the lower ends by a collar 14^a threaded right-handedly onto the lower part of the shoe.

Barrel section 13 is mounted in the mandrel in such a manner as to give the barrel a positive and powerful rotational drive from the mandrel and at the same time to allow of vertical adjustment of the barrel with relation to the mandrel and cutters 11. Depending upon the type of formation being worked in, it is desirable to have the cutting edge of the shoe a greater or lesser distance below the cutting edges of cutters 11. For instance, in soft formations it is desirable to have the cutting shoe at a greater advance below the cutters; while in harder formations it is desirable to have less advance. And we also mount the barrel in the mandrel in such a manner as to make it easily removable from the mandrel for the purpose of facilitating removal of the core from the barrel.

The barrel section 13 extends through a longitudinal central bore 25 in the mandrel. The barrel has running threads 26 cut on it, and nuts 27 and 28, running on these threads, bear on the upper and lower end surfaces of the mandrel. The lower nut may preferably be completely enclosed in a recess 29; and under both nuts, in recesses 30; there are washers 31 of leather or other suitable material that, compressed by the nuts, make a tight fit in the recess and around the barrel and thereby exclude any fine sand or silt that might otherwise find its way into the bore 25 around the barrel and thus render it very difficult to remove the barrel from the mandrel. By using these washers and thus making the bore liquid tight, we are enabled to make the bore large enough so that the mandrel slips into and out of it easily; all without danger of the mandrel becoming stuck in the bore. We do not mean by this that the bore is so large that the mandrel has any appreciable play in it, but only large enough to make for the barrel a freely sliding fit.

The barrel has on it, and preferably formed integrally with it, a key or wing 32; and the mandrel has several key slots 33 of different lengths, as will be seen by

reference to Fig. 1. Key 32 may be slipped into any one of these key slots from below, the key slots extending down to the lower end of the mandrel; and then by proper operation of nuts 27 and 28 the upper end 70 of the key may be, if desired, drawn up against the upper end of the slot in which it is placed. Through this arrangement the barrel may be placed at varying heights 75 with reference to the mandrel and cutters 11 and at the same time the barrel is given a positive and powerful driving connection with the mandrel. The upper nut 27 may be flattened off at opposite sides, so as not to cover the water circulation holes 35, as 80 shown in Fig. 3.

The barrel extension 15 we now preferably make of comparatively light sheet iron, and it is split longitudinally as indicated at 40, and this split may extend from a point near its lower end clear to its upper end. Being thus made of comparatively light material and being split longitudinally it is capable of expanding in diameter 90 if there is any tendency of the core to expand in diameter as it is pushed up through the barrel. In order to keep the core, particularly if it is of soft or sandy material, from working out through slots 40 we cover the slots with cover plates 41. It will be 95 understood that the circulation water, during drilling operations, is being constantly forced down through the interior of the drill stem; and to protect the core from this downward water current we put a cap 42 100 over the upper end of extension 15. This cap has an interior diameter larger than the exterior diameter of extension 15 so that a space is left between the two to allow 105 any water above the core to be forced out under the cap. The upper end of extension 15 may have apertures 45 and the lower end of the cap may have apertures 46; or the lower end of the cap may be open. Or, as shown in Fig. 5, the cap may be supported in such a position that its upper end 110 is spaced from the upper end of extension 15. The cap may be supported on extension 15 in any suitable manner, as by 115 rivets 47.

Having described a preferred form of my invention, we claim:

1. In combination with a rotary drilling bit, a core taking barrel centrally mounted in the bit, the barrel including a section that extends vertically through the bit from its lower surface to its upper surface, and means for holding the barrel in place including nuts threaded on the barrel and bearing on the upper and lower surface of the bit.

2. In combination with a rotary drilling bit, a core taking barrel centrally mounted in the bit, the barrel including a section that extends vertically through the bit from its lower surface to its upper surface, and means 130

for holding the barrel in place including nuts threaded on the barrel and bearing on the upper and lower surface of the bit, and washers under the nuts and tightly surrounding the barrel to exclude liquid and fine solid matter.

3. In combination with a rotary drilling bit, a core taking barrel centrally mounted in the bit, the barrel including a section 10 that extends vertically through the bit from its lower surface to its upper surface, and means for holding the barrel in place including nuts threaded on the barrel and bearing on the upper and lower surface of the bit, 15 a key on the barrel and the bit having a plurality of key receiving slots of different lengths, whereby the position of the barrel with reference to the bit may be changed by putting the barrel key into different slots.
- 20 4. In combination with a rotary drilling bit, a core taking barrel centrally mounted in the bit, an annular formation cutting shoe mounted on the lower end of the barrel, the opening through the shoe being of less diameter than the opening through the barrel; 25 and an upward barrel extension expandable in diameter.
5. In combination with a rotary drilling bit, a core taking barrel centrally mounted 30 in the bit, an annular formation cutting shoe mounted on the lower end of the barrel, the opening through the shoe being of less diameter than the opening through the barrel; 35 and an upward barrel extension of comparatively light material slotted lengthwise to allow diametrical expansion.
6. In combination with a rotary drilling bit, a core taking barrel centrally mounted in the bit and having an annular cutting

shoe at its lower end, and a cap over the 40 upper end of the barrel with its side wall spaced from the barrel wall and with an opening at its lower end, there being an opening at the upper end of the barrel into the upper part of the cap.

45

7. In combination with a rotary drilling bit, a core taking barrel centrally mounted in the bit, an annular formation cutting shoe mounted on the lower end of the barrel, the opening through the shoe being of less 50 diameter than the opening through the barrel; and an upward barrel extension of comparatively light material slotted lengthwise to allow diametrical expansion, and a cap over the upper end of the barrel extension 55 with its side wall spaced from the wall of the barrel and with an opening at its lower end, there being an opening from the upper end of the barrel into the upper part of the cap.

60

8. In combination with a rotary drilling bit, a core taking barrel centrally mounted in the bit, the barrel including a section that extends vertically through the bit from its lower surface to its upper surface, and 65 means for holding the barrel in place, including a key on the barrel and the bit having a plurality of key receiving slots of different lengths, whereby the position of the barrel with reference to the bit may be 70 changed by putting the barrel key into different slots.

In witness that we claim the foregoing we have hereunto subscribed our names this 28 day of Mar. 1923.

HARDY H. HAIR.
CHASE E. SUTTON.
